DESIGN FOR A LAMP

Itsuo Wooga, Tokyo, Japan

Application December 30, 1938, Serial No. 82,082

Term of patent 7 years

To all whom it may concern:

Be it known that I, Itsuo Wooga, a subject of the Emperor of Japan, residing in the city of Tokyo, Empire of Japan, have invented a new, original, and ornamental Design for a Lamp, of which the following is a specification, reference being had to the accompanying drawing, forming a part thereof.

The figure is a perspective view of a lamp, embodying my new design.

The design is characterized by a supporting base with a handle attached thereto, and a translucent globe in the shape of a fish, of the configuration shown.

I claim:

The ornamental design for a lamp, substantially as shown and described.

ITSUO WOOGA.
